(Cl. D15—8)

In the drawing, the figure illustrates a perspective view of a pillow embodying my novel design.

The side surface opposite to that shown in the figure is the mirror image of the side surface shown in the figure. The back surface and the bottom surface are rectangular and flat.

The design is characterized by the front surface thereof, said front surface being comprised of upper and lower concave sections joined smoothly together by an intermediate convex section, the lower concave section terminating in an elongated generally flat inclined section, all as shown.

I claim:

The ornamental design for a pillow, as shown and described.
